UNITED STATES PATENT OFFICE

2,313,541

MACHINE FOR PURIFYING LIQUIDS

Alan E. Flowers, Poughkeepsie, N. Y., assignor to
The De Laval Separator Company, New York,
N. Y., a corporation of New Jersey

Application May 26, 1941, Serial No. 395,153

1 Claim. (Cl. 233—15)

My invention relates to the removal of objectionable matter from liquids, and comprises a novel type of centrifugal separator adapted to effect this result with maximum efficiency. The invention is particularly adapted for removal of reaction products from vegetable and animal and other oils which have been chemically treated to neutralize deleterious constituents therein.

It is well known that in both gravity and centrifugal treatments it is relatively easy to remove a major portion of reaction products while it is relatively difficult to remove a small minor portion of these products. It is also well known that many of these products are easily soluble in water or other liquids having a greater specific gravity than the oil being treated and it is common practice to carry out first a gravity or centrifugal separation of most of the reaction products and then follow with a wash with a suitable liquid and cause a second independent gravity or centrifugal separation of the wash liquid and accompanying impurities.

When such a two-step separation has been carried on in the past it has required the use of two centrifugal machines in series, or the storage of primarily separated liquid until after treatment of an entire batch and then the use of the same separator, perhaps with a different adjustment, for the removal of wash liquid with its contained impurities.

Specifically, the object of my invention is to provide a centrifugal bowl in which these primary and secondary purification steps may be effected in a single centrifugal operation, that is, to provide a single centrifugal bowl in which the primary separation of a major portion of the impurities takes place first, followed by the dissemination of a washing liquid through the partially purified liquid and the separation of that wash liquid and its contained impurities therefrom so that both operations can be effected in a single pass.

The single figure of the accompanying drawing is a section, in a plane, passing through the axis, of a bowl adapted for practicing the described process.

Certain structural features of the bowl are found in the Hall Patent No. 1,411,782, issued April 4, 1922, which provides means for independently feeding two separate liquids to two different zones in a centrifugal bowl; but the construction embodying my invention differs essentially from the construction of the Hall patent in respect to features particularly adapted for the practice of the described process.

1 is a bowl shell having a bottom 2 with a socket 3 fitting the driving and supporting spindle 4. The bowl top 5 has a discharge outlet 6 at the upper end and is secured to the bowl shell by 5 the coupling ring 29. In the center of the bowl is a tube 7 enclosing a feeding passage 8 from which several channels 9 lead to distributing holes 25 through the frusto-conical member 21, technically called discs. Only a few of these discs are shown. Inside tube 7 is a second tube 11 enclosing another feed passage from which several channels 12 lead. Up to this point the construction is in the manner of the Hall patent before mentioned and is therein clearly shown 10 and described.

Each of the channels 12 terminates at the entrance 13 to a tube 14 which communicates with the interior of the separating chamber of the bowl through only tiny slits or holes 15 in the 20 tube wall so arranged that they feed to the spaces between the discs 21. In the upper part of the bowl a top disc 16 provides a division wall between the separating chamber of the bowl and the passages 17 leading to the discharge outlet 25 6. Passages also lead from the inner edges of the discs 21 upward inside the neck of the top disc 16 to the outlet 18 for the discharge of the light oil.

Wings 19 between the bowl top 5 and the top 30 disc 16 and wings 20 secured to the bowl shell and extending inward to near the outer edge of the discs 21, force the bowl contents to continue rotating at the same speed as the bowl. Wings 26 and 27 attached to the walls of the tubes 11 35 and 7 respectively, force the incoming liquids to assume a speed of rotation equal to that of the bowl. Covers 22 are supplied to provide chambers to catch the materials discharged from the bowl. Supported by suitable means are two concentric supply tubes 23 and 24 which extend down 40 inside the upper ends of the tubes 11 and 7 respectively.

While the bowl is useful for the removal of reaction products from any liquids, among which 45 are vegetable, animal and mineral oils and other substances, in which chemical or physical treatment has produced materials having a specific gravity different from that of the liquid being treated and soluble in or combinable with some 50 washing liquids, I will describe its use for only one class, vegetable oils, which, when separated from the vegetable matter in which they originated, contain objectionable acid materials that can be neutralized with alkalies and then form 55 water soluble soaps.

In the operation of the bowl, alkali treated oil containing the resultant soap is fed to the bowl through the tube 24, flows downward through passages 8 inside the tube 7 and outward through channels 9 to the entrance to the distributing holes 25 in the discs 21, thence upward through the distributing holes and spreads out between the discs. There a major portion of the soap is separated from the oil and flows outward to the periphery of the bowl, then upward and inward between the top disc 16 and the bowl top, and escapes through the neck 6.

The oil containing a minor residual portion of the soap flows toward the center of the bowl.

At the same time, clean water is supplied to the bowl through tube 23, flows downward inside tube 11, outward through channels 12 and upward in the tubes 14 whence it is discharged through tiny holes or slits 15 in the tube walls and, while moving outward toward the periphery of the bowl, is disseminated through the inwardly flowing oil where it combines with the residual soap not previously removed. This water and soap mixture flows outward between the discs and joins with, and flows out of the bowl with, the previously separated major portion of the soap.

The washed oil continues its flow toward the center of the bowl, thence upward and discharges at 18.

By placing the distributing holes 25 near the periphery of the discs and the wash water feeding tubes 15 near their inner edges, a long counterflow of the water and oil with consequent good washing of the oil is obtained.

What I claim and desire to protect by Letters Patent is:

In a centrifugal separator for the separation from a liquid containing impurities of heavier specific gravity than the liquid, comprising a separating bowl and contained therein a plurality of frusto-conical discs providing a plurality of frusto-conical separating chambers, means to feed the impure liquid to said separating chambers through said discs between their inner and outer edges, in which chambers, under the action of centrifugal force, said liquid with a minor part of its impurities is separable from the major part of its impurities and is displaced inward toward the bowl's axis while the separated impurities move outward toward the periphery, and means to disseminate a washing liquid heavier than the liquid to be purified throughout said separated partially purified liquid, said means including a supply conduit extending through said bowl and having outlets which open into the inner parts of said separating chambers and nearer the axis of the bowl than the admission means for the impure liquid and which are so restricted as to effect proper distribution, thereby causing combination of said washing liquid with the impurities in the partially purified liquid, and the separation of said washing liquid and impurities from substantially purified liquid and movement of said washing liquid and impurities outward through said separating chambers toward the bowl's periphery, the separator having the usual outlets for lighter and heavier separated constituents through which are respectively discharged the purified liquid and the washing liquid and impurities.
